CURTAIN FOR A CHILD'S NURSERY ROOM

Maude P. Collester, New York, N. Y., assignor to
I. B. Kleinert Rubber Co., New York, N. Y., a
corporation of New York

Application February 10, 1949, Serial No. 75,526

7 Claims. (Cl. 160—127)

1

The invention relates to a curtain construction intended for use in a child's nursery room and which is provided with a plurality of pockets adapted to hold toys or other articles.

The object of the invention is to provide a novel and decorative curtain construction adapted to be used in a child's nursery room and which is so constructed that it is provided with a separable back panel containing a plurality of pockets therein in which toys or other play articles of the child may be received.

In a child's nursery room there is usually a number of toys or other play articles which are left around on the floor or elsewhere at the end of a day which must be picked up and put away so that the room will have a tidy appearance. Ordinarily this picking up and storage of the toys or other articles must be done by the parent or by a nurse, and necessitates placing the same in some suitable place, such as in a closet or cabinet which is inaccessible to the child and then when the toys are to be used again, it is necessary for the parent or nurse to remove the same from their storage place and give them back to the child. The present invention is designed to overcome this situation by providing a curtain construction which may be hung either at a window in the nursery room or at some other place in the room, and which is so constructed and arranged that it will provide an easily accessible place where the child, itself, may put away the toys and play articles after playing with them, and take them out again when desired.

In the accompanying drawings I have illustrated my improved curtain and the several views therein show the following:

Figure 1 is a front elevation of a curtain made in accordance with my invention, with parts shown broken away to more clearly indicate the construction thereof.

Figure 2 is a broken plan view of the curtain construction showing the same in an opened out flat condition, and particularly showing the inner face of the back panel thereof.

Figure 3 is a sectional view of Figure 1, taken on the line 3—3 looking in the direction of the arrows.

Figure 4 is a sectional view of Figure 1, taken on the line 4—4 looking in the direction of the arrows.

Figure 5 is a sectional view of Figure 2, taken on the line 5—5 looking in the direction of the arrows.

The curtain construction of the invention may be used either as a window curtain or as a decora-

tive hanging to be hung on a wall or at any other suitable location in the nursery play room. The curtain is made with a front panel, indicated generally by the numeral 1, and a back panel, indicated by the numeral 2. The front panel 1, may be made of any suitable decorative fabric material and provided with a suitable ruffle 3, around its outer edges, and with an upper hem 4, so constructed and sewn that a curtain rod or similar hanging support may be inserted therethrough.

The back of the material of the front panel 1, is reinforced by sewing to it, along its edges, a suitable fabric material such as is indicated at 5, in Figure 2. Sewed to the back of the fabric material of panel 1, and to the backing material 5, and along the line 6, is the upper edge of a back panel 2. The inner face of said back panel may be formed of a suitable quilted fabric material 7, and the outer face of said panel is formed of a plain fabric material 8, which is sewed to the quilted fabric material 7, along the edges thereof and reinforced along said edges by a suitable binding 10.

Sewed to the inner face of panel 2, are the pocket panels 11 and 12. These panels may be made of a quilted fabric material similar to that used for the inner face of panel 2, and their inner faces may be reinforced by a plain fabric material 9, of the type similar to that used for the outer face of panel 2.

The pocket panel 11 is formed with the curved top edges 13 and 14 which at their inner portions curve upwardly and from the upwardly extending tab 15. The top edge 16, of the tab 15, is sewed to the top edge of the back panel 2 and also to the front panel 1, along the line 6. The side edges 18 and 19 of pocket panel 11 are sewed to the side edges of the back panel 2, and the bottom edge 20 thereof is sewed to the back panel along the line 21.

Thus there is formed an upper pocket A on the inner face of the back panel 2 which is adapted to receive and hold toys and other play articles.

The pocket panel 12 is formed in a similar manner to pocket panel 11, and so that it is provided with the curved top edges 22 and 23 which at their inner portions curve upwardly and from the upwardly extending tab 24, and the top edge 25 of said tab is sewed to the panel along the line 21. The side edges 27 and 28 of the pocket panel 12 are sewed to the side edges of the back panel 2, and the bottom edge 29 thereof is sewed to the bottom edge 30 of said back panel. There is thus formed a lower pocket

55 B, on the inner face of the back panel 2, which

is also adapted to receive and hold toys or other play articles.

It will be noted that by reason of the construction as above described, the pockets A and B are positioned behind and facing the back face of the front curtain panel 1, and thus when toys or play articles are placed in said pockets they will be covered by both the front panel and the outer face of the back panel of the curtain and will be thus concealed from view. Also the pockets 10 A and B are positioned so that they will be readily accessible to a child and so that the child may without trouble remove and replace the toys or play articles.

Although the curtain illustrated in the drawings is shown as provided with only two toy receiving pockets, it is to be understood that more pockets may be provided without departing from the spirit of the invention. Also, although the curtain as shown in the drawings is intended to be used as a window curtain, it is obvious that it also may be used as a decorative panel or drape to be hung elsewhere in the nursery play room.

What is claimed is:

1. A curtain for a child's nursery room comprised of a front panel made of a reinforced decorative fabric material, a rear panel joined at its upper edge to the upper edge of the front panel and made of a quilted fabric material, and a plurality of pockets made of a fabric material similar to the fabric material of the rear panel and sewed to the inner face of said rear panel, said front panel concealing said rear panel and pockets from view when said pockets are in use.

2. A curtain for a child's nursery room comprised of a rectangular shaped reinforced fabric panel, a second fabric panel positioned behind said first mentioned panel and joined at its upper edge to the upper edge of the first mentioned panel, and a plurality of pockets made of a fabric material and sewed to the inner face of said rear panel, said first mentioned panel concealing said second panel and pockets from view when said pockets are in use.

3. A curtain for a child's nursery room comprised of a front panel of a decorative fabric material provided with a reinforcing backing made of a different fabric material which is sewed along its edges to the rear face of said front panel, a rear panel made of a quilted fabric material having its upper edge sewed to the upper edge of the front panel and provided with a reinforcing backing made of a different fabric material than the fabric of the rear panel, and a plurality of reinforced fabric panels having their side and bottom edges and a portion of their top edges sewed to the inner face of said rear panel to form pockets on said inner face of said panel, said front panel concealing said

rear panel and pockets from view when said pockets are in use.

4. A curtain for a child's nursery room comprised of a rectangular shaped outer fabric panel and a rectangular shaped inner fabric panel, said panels being sewed together at their upper edges, said outer fabric panel being provided with ruffles along its side and bottom edges and a hem at its top edge for receiving therethrough a curtain rod, said inner fabric panel being made of a quilted fabric material and having a plurality of pockets, made of the same material, sewed to the inner face thereof, said outer panel concealing said inner panel and articles placed in said pockets when said pockets are in use.

5. A curtain for a child's nursery room comprised of a rectangular shaped panel made of a decorative fabric material with a reinforcing backing made of a different fabric material which is sewed to the rear face thereof, a rear panel made of a quilted fabric material sewed at its upper edge to the first mentioned panel and having a reinforcing backing made of a different fabric material which is sewed to the rear face thereof, and a plurality of reinforced fabric panels with curved upper edges and having their side and bottom edges and a portion of their upper edges sewed to the inner face of said rear panel and forming pockets on said inner face of said panel, said first mentioned panel concealing said rear panel and articles placed in said pockets from view when said pockets are in use.

25 6. A toy holding curtain for a child's nursery room comprised of a rectangular shaped reinforced fabric panel, a second reinforced fabric panel sewed at its upper edge to the upper edge of said first mentioned panel, and a plurality of pockets formed on the inner face of said second panel by fabric panels having their side and bottom edges sewed to the said inner face of said panel to form toy holding pockets, said first mentioned panel concealing said second panel and said pockets from view.

30 7. An article storing curtain comprising a front fabric panel and a rear fabric panel joined at their upper edges, said front panel having an area covering said rear panel substantially completely, and a plurality of fabric pockets sewed to the inner face of said rear panel.

MAUDE P. COLLESTER.
